CASE FOR SAFETY RAZOR SET

Alan Gunston Tye, 189 Spring Grove Road,
Isleworth, Middlesex, England

Filed Nov. 16, 1962, Ser. No. 72,515

Term of patent 14 years

(Cl. D58—12)

FIG. 1 is a view in perspective of a case for safety razor set showing my new design,

FIG. 2 is a top plan view thereof;

FIG. 3 is a front elevational view thereof;

FIG. 4 is a right-side elevational view thereof, the left side being substantially a mirror image thereof;

FIG. 5 is a fragmentary top plan view of the base portion thereof;

FIG. 6 is a cross-sectional view thereof taken on line 6—6 of FIG. 2;

FIG. 7 is a rear elevational view thereof; and

FIG. 8 is a bottom plan view thereof.

I claim:

The ornamental design for a case for safety razor set, substantially as shown.
